UNITED STATES PATENT OFFICE.

JAMES R. WYATT, OF PHILADELPHIA, PENNSYLVANIA, ASSIGNOR TO THE AJAX METAL COMPANY, OF PHILADELPHIA, PENNSYLVANIA, A CORPORATION OF PENNSYLVANIA.

TILTING MECHANISM FOR CONTAINERS, SUCH AS FURNACES.

Application filed November 8, 1918. Serial No. 261,670.

To all whom it may concern:

Be it known that I, JAMES R. WYATT, a citizen of the United States, residing at 2024 S. 21st Street, Philadelphia, in the 5 county of Philadelphia and State of Pennsylvania, have invented a certain new and useful Tilting Mechanism for Containers, Such as Furnaces, of which the following is a specification.

10 My invention relates to counter-balancing and tilting mechanism capable of being applied to furnaces for melting metal but having a more general application.

The purpose of my invention is to provide counter-balancing and tilting mechanism which shall turn the container about a predetermined point outside of its center of gravity, and preferably about the spout, so that the pouring point shall be as nearly 20 fixed as possible.

A further purpose is to locate the bulk of the mechanism for tilting the container beneath the container and as much of it as practicable beneath the floor.

25 A further purpose is to lift the container by a system of levers and supporting bars and to swing it by bars which may also form supports, distributing the lifting and swinging functions as may be desirable. In its 30 best form the lifting and directing arms and bars are arranged in parallel pairs.

A further purpose is to provide for application and adjustment of the counter-balancing weight to the best advantage.

35 Further purposes will appear in the specification and in the claims.

I have preferred to illustrate my invention by but one general form thereof, selecting therefor a form which in use has proved 40 to be simple, practical, highly efficient and inexpensive and which at the same time well illustrates the principles thereof.

Figure 1 is a broken side elevation showing this preferred form of my invention.

45 Figure 1^a is a broken side elevation of a modification.

Figure 2 is a section upon line 2-2 of Figure 1.

Figure 3 is a broken side elevation of the 50 same structure with the furnace in raised position.

Figure 4 is a front elevation of the structure in Figures 1 and 2 with part of the counter-balancing weights broken away.

In the drawing similar numerals indicate 55 corresponding parts.

Though my invention is suited to the lifting and tilting of any container which is desirably tilted about a point outside of its center of gravity its greatest usefulness thus 60 far has been found in furnaces. As I have applied it to electric furnaces of the type shown in my Patent No. 1,201,671 of Oct. 17, 1916, I have preferred to illustrate it and describe it in connection with and in terms 65 of such an electric furnace but without any intention of limiting it to such use alone.

The furnace shown has been fully described in my patent. It will suffice to say that it comprises a body 5 providing a pool, 70 connecting with a member 6 providing a channel in which the metal is heated and circulated by electric current induced by means of a transformer 7. The transformer winding 8 is connected with the current supply 75 by extensible leads not shown, permitting the tilting movement or is disconnected for pouring as preferred. As my furnace maintains the electric current path during pouring there is a considerable advantage 80 in maintaining the current flow then also. The spout is shown at 9 and the body, channel and spout are suitably lined.

Describing the preferred construction:—

In any pair of pedestals 10 I support a 85 counterweight-lever shaft 11 rigidly secured to a pair of levers 12, by screws 13 passing through bosses 14. The axis of the shaft is indicated at 11'. The levers 12 are made up of counterweight-supporting arms 90 15 at one end and furnace-supporting arms 16 at the other end.

The mechanism for turning the shaft illustrated comprises a worm wheel 17, turned by a worm 18, upon shaft 19. Mitre gears 95 20 connect this shaft with a control shaft 21 surmounted by hand wheel 22. For clearness in illustration I have omitted the usual bearings for shafts 19 and 21. The arms 15 of the counterweight levers, are connected 100 at their ends by a channel bar 23, upon which separate counterweights 24 may be placed. The weights are slotted upon their under sides to pass over the bar 23 from above and remain in position because of 105 gravity alone.

For adjustments not requiring as much additional weight as is represented by a

counterweight 24, I provide one or more sliding counterweights 26, similarly slotted so as to fit over and slide upon the arms 15 and secured in adjusted positions by any means, such as set screws 27; with the purpose that the weight or weights 26 shall provide all intermediate counterweight adjustments between that secured by different weights 24.

10 The levers 12 are connected with the furnace by two supporting bars 28, one on each side of the furnace, which are pivoted to the arms 16 of the levers, as by pins 29 having a common axis 29', and to the furnace 15 by trunnions 30 having a common axis 30'. Suitable split pins retain all such pivoted parts in position.

10 The bars 28 must be held in approximately perpendicular position and this is 20 conveniently taken care of by arms 31 which may be pivoted in the pedestal 10 about pins 32 having a common axis 32', and to the bars 28 by pins 33 having a common axis 33'. The bars 28 may be maintained 25 in vertical position by making the spacing between axes 32' and 33' equal to that between axes 11' and 29', and the spacing between axes 32' and 11' equal to that between axes 33' and 29' (i. e. making the 30 figure involved a parallelogram).

However, since the chief and, permissibly, the only function of arms 31 (since the tilting connections can be operated from arm or arms 16) is to maintain bars 28 within 35 the designed approximations to or range from their initial angular directions, any departure from true parallelogram form may be utilized.

40 Downward movement of the furnace is conveniently limited by making the arms 16 or the bottoms 34 of bars 28 engage a stop, as 35.

Where it is intended to support the entire weight of the furnace by the bars 28, 45 the axis 30' is chosen so as to intersect a vertical line through the center of gravity of the furnace, preferably near the center of gravity of the furnace when fully charged. If at least as high as the center 50 of gravity of the fully charged furnace, there will be no tendency of the furnace to swing when in the position shown in Figure 1.

It will be obvious that the support of the 55 furnace may be divided between the bars 28 and some other bar, such as 36, or preferably bars on opposite sides of the furnace by which the turning of the furnace may be effected and I have shown such a construction in Figure 1^a, where the bars 28' are connected with the furnace about some other axes 30' which does not pass through the vertical line from the center of gravity of the furnace and the unbalanced weight of

the furnace and content are supported by 65 bars 36'.

Whether the bars 36 or 36' be intended for tilting purposes chiefly, or for supporting any considerable share of the weight of the furnace, it will be obvious that the strain 70 (and possibly pressure) upon it will vary with variation in the center of gravity during the pouring operation.

In either event, the bars 36 or 36', are pivoted to the furnace at one end, as about 75 trunnions 37 having a common axis 37', and to one of the arms, 16 and 31, preferably to the upper of these in order to reduce the length of bars 36 or 36'. I prefer to connect the bars 36 or 36' with the arms 16 or 80 31, as the case may be, by pins 38, having a common axis 38', located between bars 28 and the pedestals, as shown, because this construction permits the use of shorter arms 16 or 31 (which then need not be extended 85 beyond the bars 28), gives a better lifting moment and forms a more compact construction.

By making the distances between the axes 30' and 37' equal to those between axes 33' 90 and 38' the distances between axes 33' and 30' equal to the distance between axes 37' and 38' (i. e. making this figure also a parallelogram) the furnace will tilt throughout its movement about a single axis, which 95 is the intersection of the plane through axes 30' and 37' with the plane through axes 11' and 32'. The positions of these planes are shown by lines 39 and 40 and the turning axis is located at 41, all in Figure 1. By 100 elemental design, the axis, at which there will be neither vertical nor horizontal movement, but only turning movement, may therefore be made to pass through the outer end of the pouring spout, as shown in Figure 1, or any other point desired such as the 105 base of the pouring spout in Figure 1^a. The fixing of the pouring point greatly simplifies and facilitates the pouring, secures greater precision and safety and avoids undue movement of the molds.

I recognize that variations from parallelism of the bars 28 and 36 and of the connecting parts forming this second parallelogram would still secure desirable results including the same initial and final positions of the spout with little movement between and that but one bar 36 may be required. For some purposes it may be desirable to depart from parallelism of the arms and 110 bars respectively, or to alter the other sides of the quadrilaterals formed, in order to accelerate or retard the relative rate or vary the total movement of the parts of the furnace, all of which can be worked out readily 115 to suit the conditions of any equipment, or the whim or preference of any designer in view of the information given by me.

In operation the furnace is loaded and operated in the position shown in Figure 1. The counterweighting will normally represent a mean between that needed for the furnace when filled and that required for the furnace when a charge has just been poured. Under these circumstances, the overbalancing weight of the content will tend to hold the furnace down in the position shown when 5 fully charged and during the heating operation. The furnace will therefore offer an opposing overbalance to the tilting operation by hand wheel 22. The tilting of the furnace 10 will take place coincidentally with the lifting. Where enough of the content has been poured for the furnace and remaining content to be over-balanced the counterweighting will tend to lift the furnace. When the heat has been poured approximately as much 15 effort upon hand wheel 22 will be required to lower the furnace as had previously been required to raise it.

The position shown in Figure 3 is selected to correspond with the maximum tilting for 20 pouring for which the furnace is designed and will normally not permit draining of any part of the channel.

Having thus described my invention, what I claim as new and desire to secure by 25 Letters Patent is:

1. In lifting and tilting mechanism, a pair of quadrilateral systems of arms, bars and pivotal connections on each side of a furnace having part of one quadrilateral system forming part of the other, counterweighting mechanism for the system and a container forming one side of one quadrilateral system and lifted and tilted thereby.

2. In lifting and tilting mechanism for 40 containers, a quadrilateral system of lifting, guiding arms and counter-weighting connections, in combination with a container and a quadrilateral system of bars and connections interconnected with the first quadrilateral system to lift and tilt the container.

3. In tilting mechanism for pouring from a container, counterweight levers, terminating in lifting arms below the container, a container, approximately vertical supporting bars connected with the levers and container, arms connected at one end with the bars to maintain them in substantially vertical position and a tilting bar connected with the container at one end and with one of 55 the arms at the other end.

4. In tilting and pouring mechanism for 60 containers, a pair of levers having lifting arms, a pair of supporting bars on opposite sides of the container, connected with the arms at one end of each and with the container at the other end thereof, a container, guiding arms for maintaining the supporting bars against undue swinging movement, counterweighting mechanism for the sys-

tem and a tilting connection between one of 65 the arms and the container.

5. In tilting and pouring mechanism for 70 containers, a container, a pair of levers on opposite sides of the container and having lifting arms, bars pivotally connected to these arms and to the container, guiding and side supporting arms for these bars substantially parallel with the lifting arms, counterweighting mechanism for the system and a 75 bar pivotally connected with one of the arms and with the container cooperating with the first bars in tilting the container.

6. In tilting and pouring mechanism for 80 containers, a container, levers therefor having lifting arms, connections therefrom supporting the major part of the weight of the container, guiding and side supporting arms for the connections, substantially parallel with the lifting arms, counterweighting mechanism for the system and a connection 85 from the container to one of the arms engaging it at an intermediate point.

7. In tilting and pouring mechanism for 90 containers, a container, levers adapted to turn about an axis and having supporting arms, supporting bars pivoted to these arms at one end of each and to the container at the other end of each, guiding arms having fixed pivots at one end of each and connected with the bars at the other end of each, 95 counterweighting mechanism for the system and a tilting connection between one of the arms and the container substantially parallel with one of the supporting bars.

8. In tilting and pouring mechanism for 100 containers, a pair of levers adapted to turn about an intermediate axis and having lifting arms, supporting bars connected with the levers at one end and with the container at the other end, guiding and side supporting arms having fixed pivot points at one end, connected with the bars at the other end and substantially parallel with the lifting arms, counterweighting mechanism for the 105 system and a tilting connection between one of the arms and the container substantially parallel with the supporting bars and located between the supporting bars and the fixed pivot points.

9. In tilting and pouring mechanism for 110 containers, a container, a pair of levers, a connection between them joining them at one end of each lever so as to cause them to move together, the levers being pivoted at an intermediate point and extending in the 115 form of supporting arms at their other ends, supporting bars pivoted to these arms at the ends and to the container, guiding arms having fixed pivots at one end, extending substantially parallel to the supporting 120 arms and pivoted at their other ends to the bars, counterweighting mechanism for the 125 system and tilting bars pivoted to the guid-

ing arms at one end and to the container at the other end.

10. In tilting and pouring mechanism for containers, a container, a pair of levers, a connection between them joining them at one end of each lever so as to cause them to move together, the levers being pivoted at an intermediate point and extending in the form of supporting arms at their other ends, 10 supporting bars pivoted to these arms at the ends and to the container, guiding arms having fixed pivots at one end, extending substantially parallel to the supporting arms and pivoted at their other ends to the bars, 15 counterweighting mechanism for the system and tilting bars pivoted to the guiding arms at one end and to the container at the other end, the planes through the axes of the different arms and through the container pivots 20 of the bars, respectively, determining the axis of revolution of the container.

11. In tilting and pouring mechanism for containers, a container, a pair of levers, a connection between them joining them at 25 one end of each lever so as to cause them to move together, the levers being pivoted at an intermediate point and extending in the form of supporting arms at their other ends, supporting bars pivoted to these arms at 30 the ends and to the container, guiding arms having fixed pivots at one end, extending substantially parallel to the supporting arms and pivoted at their other ends to the bars and tilting bars, counterweighting mechanism 35 for the system pivoted to the guiding arms at one end and to the container at the other end, the planes through the axes of the different arms and through the container pivots of the bars, respectively, passing approximately 40 through the pouring spout of the container.

12. A counterweighting and tilting mechanism for one side of a furnace comprising a pair of parallel arms one above the other and both having fixed pivot points, worm wheel tilting means for one of the arms, an extension from one of the parallel arms, a counterweight upon the extension, a connection between the parallel arms and a pair of 50 supporting and tilting bars extending from one of the parallel levers to pivot points upon the container and stiffened against improper turning by connection with the other of the parallel levers, in combination with

counterweighting connections for the other 55 side of the furnace.

13. A counterweighting and tilting mechanism for pouring from furnaces, comprising sets of parallel arm and bar constructions on opposite sides of the furnace, each made 60 up of a pair of parallel arms having fixed pivot points, tilting means for one of the arms, a counterweighting extension from one of the arms, a connecting bar between the parallel arms, extended and pivoted to 65 the furnace and a second bar connected with one of the parallel arms and pivoted to the furnace at a distance from the pivot point of the extended arm.

14. Counterweighting and tilting mechanism 70 for a furnace comprising pairs of parallel arms spaced and pivoted at fixed pivot points, one above the other, a line through the pivot points cutting the axis about which the furnace turns, counterweighting extensions from one of said arms of each pair, a shaft connecting the counterweighted arms, worm and worm wheel tilting means for said shaft and arms, a connection between the parallel arms on each side of the furnace 75 extended and pivoted to the furnace and a connection between the furnace and one of said parallel arms pivoted to the furnace, so that a line through the furnace pivot points will intersect the intended axis 80 of turning of the furnace.

15. In lifting and tilting mechanism, a container, a lever lifting mechanism therefor, counterweight arms for said lever system, a transverse connection between the 90 outer ends of the arms, counterweights on the transverse connection and counterweights on the arms adjustable toward and from the pivot point of the arms.

16. In lifting and tilting mechanism, a 95 container, a lever lifting system therefor, counterweight arms for said lever system, a transverse connection between the outer ends of the arms, counterweights on the transverse connection and counterweights on the 100 arms adjustable toward and from the pivot point of the arms and covering in that range of adjustment the difference in counterweighting represented by use or non-use of one of the transversely placed counterweights.

JAMES R. WYATT.
